UNITED STATES PATENT OFFICE

127,313

DESIGN FOR A DISPENSING CONTAINER

Robert J. Wilkie, Minneapolis, Minn., assignor to Continental Machines, Incorporated, Minneapolis, Minn., a corporation of Minnesota

Application March 5, 1941, Serial No. 99,363

Term of patent 7 years

To all whom it may concern:

Be it known that I, Robert J. Wilkie, a citizen of the United States residing at Minneapolis, in the county of Hennepin and State of Minnesota, have invented a new, original, and ornamental Design for a Dispensing Container, of which the following is a specification, reference being had to the accompanying drawing, forming part thereof.

I claim:

The ornamental design for a dispensing container, as shown and described.

ROBERT J. WILKIE.
